UNITED STATES PATENT OFFICE.

ARTHUR W. RIVETT, OF CHICAGO, ILLINOIS, ASSIGNOR TO J. J. RYAN & CO., OF SAME PLACE.

DESIGN FOR A SPROCKET-WHEEL AND CHAIN GUARD.

SPECIFICATION forming part of Design No. 27,184, dated June 8, 1897.

Application filed April 24, 1897. Serial No. 633,816. Term of patent 3½ years.

To all whom it may concern:

Be it known that I, ARTHUR W. RIVETT, of Chicago, in the county of Cook and State of Illinois, have invented and produced a certain new and useful Design for Chain and Sprocket-Wheel Guards for Bicycles, of which the following is a specification.

Referring to the drawings, Figure 1 is a perspective view of a chain and sprocket-wheel guard embodying my design. Fig. 2 is a transverse vertical sectional view taken on line 2 2 of Fig. 1, the central part of the view being broken out to reduce the height of the figure.

A guard embodying this design comprises among its essential features an outer rim or open frame A, of generally oblong shape and wider at one end than at the other, the front end a, which is the wider, being formed on a true circle, to conform to the periphery of the driving sprocket-wheel of the bicycle, and the side margins a' a² being straight and arranged to converge from front to rear of the guard. The rear end a³ is also made round-

ing, but is not necessarily accurately circular, and is provided at the center thereof with an interruption or opening a⁴, which is occupied by the lower rear fork member of the bicycle-frame when the guard is in position upon the bicycle. The outer rim or frame thus formed presents a smooth and continuous outline which is not only of graceful and neat appearance, but also serves to effectually protect the garments of the rider from being caught or soiled in the chain or sprocket of the bicycle. In order to still further enhance the appearance of the guard, the said outer frame or rim is made of curved form in cross-section, the outside case being convex and so

formed that the extreme inner margins a⁵ thereof will stand in the same plane with the outer vertical face of the guard and will curve or roll over from said inner margin outwardly and toward the back side of the guard, as best indicated in sectional view Fig. 2. The rim A is provided with an instanding flange A', having substantially the same curvature in cross-sectional form and being formed in continuation of the curvature of the rim, said flange being arranged to extend practically the full length of the upper side member, around the circular front end of the guard,

and a short distance along the lower side thereof, as indicated clearly in Fig. 1, the depth or width of the flange being such as to 55 overlie the front sprocket-wheel and chain and thus both protect the latter from dust and dirt and aid in preventing the garments of the rider from coming in contact with the moving parts of the vehicle. The outer frame 60 thus formed is filled in in part with open-work of ornamental design, which forms an essential and distinct feature of the design. A circular opening a⁶ is formed within the front end of the guard concentrically with said circular end, which opening is bounded or outlined by a smooth and continuous narrow ring A². A³ designates a ring-segment formed upon the same diameter and arranged to extend in continuation of the inner margin of 65 the circular end of the outer frame, an annular space a⁷ being thus formed between the outer and inner ring members, which is filled with a geometrical pattern consisting of a series of contiguous radially-disposed Gothic 70 arches a⁸.

Immediately in rear of the ring-segment A³ is arranged a pair of oppositely-disposed ogee-shaped scrolls a⁹, said scrolls being arranged so that two of their branches a¹⁰ meet each other on the median line of the guard, while the rear ends of the scrolls extend divergently from each other and are connected with the respective inner side margins of the outer frame. A smaller scroll a¹¹ is interposed between the front end of each scroll a⁹ and the vertically-opposite portion of the outer frame. The rear end of the guard is left entirely open or unprovided with grille-work throughout approximately one-third of the full length of 90 the guard.

I claim—

The design for a chain and sprocket-wheel guard for bicycles, substantially as herein shown and described.

In testimony that I claim the foregoing as my invention I affix my signature, in presence of two subscribing witnesses, this 22d day of April, A. D. 1897.

ARTHUR W. RIVETT.
